UNITED STATES PATENT OFFICE.

WILLIAM HULL BROWNING, OF RYE, NEW YORK.

CARBURETER.

1,026,491.

Specification of Letters Patent. Patented May 14, 1912.

Application filed November 2, 1910. Serial No. 590,328.

To all whom it may concern:

Be it known that I, WILLIAM H. BROWNING, a citizen of the United States, and a resident of Rye, in the county of Westchester and State of New York, have invented a new and Improved Carbureter, of which the following is a full, clear, and exact description.

The object of the invention is to provide a new improved carbureter, for use in gasoline and like explosive engines, and arranged to permit convenient and accurate adjustment of the needle valve by bodily moving the same instead of turning and screwing the needle valve in or out, and to hold the members of the air admission valve in firm contact with each other by the suction of the engine in drawing in the air.

For the purpose mentioned use is made of a manually-controlled device for moving the needle valve bodily toward and from its seat to govern the flow of gasoline or other liquid, and an air admission valve is mounted to turn and pressed on by a spring and by the suction action of the engine to hold the air admission valve in contact with its seat.

A practical embodiment of the invention is represented in the accompanying drawings forming a part of this specification, in which similar characters of reference indicate corresponding parts in both views.

Figure 1 is a sectional side elevation of the carbureter on the line 1—1 of Fig. 2; and Fig. 2 is a plan view of the same.

The carbureter casing A is provided with a top plate B having one or more openings B' for the passage of air into the casing A, and the said top plate B is provided with a central upwardly-extending flange B², engaged by the hub C' of an air admission valve C resting on the upper surface of the top plate B and having openings C² adapted to register with the openings B' to control the amount of air passing into the casing A. The air admission valve C is provided with a handle D under the control of the operator for turning the valve C to move the openings C² in more or less register with the openings B' for the purpose specified. The turning motion of the admission valve C is limited by stops E, E' held on the side of the casing A and adapted to be engaged by the handle D. Thus

when the handle D is against the stop E, 55 the admission valve is completely open, and when the handle D abuts against the stop E' the admission valve is completely closed.

In the flange B² screws a tube F provided at its lower end with a valve seat G connected with a pipe H extending through the side of the casing A to the outside thereof to connect with a source of gasoline or other liquid supply. The valve seat G is controlled by a needle valve I, having its stem I' threaded and extending centrally through the tube F and its cap plate F', as plainly indicated in Fig. 1, and on the stem I' screws a collar J fitting into the tube F and pressed on by a spring K held in the upper 60 portion of the tube F and abutting with its upper end against the cap plate F' while the lower end of the spring engages the top of the collar J to press the latter downward and with it the stem I' and the needle 65 valve I.

On the top of the cap plate F' is mounted to turn a face cam N having a handle N' under the control of the operator, and the face cam N is engaged by an arm O guided 80 vertically on a guide pin P attached to the admission valve C. Through the arm O passes a collar Q screwing on the upper portion of the threaded stem I' of the needle valve I, and slidingly engaging the arm O, 85 face cam N and cap plate F', and on the outer end of the collar Q screws a nut R resting on top of the arm O so as to limit the downward movement of the needle valve I. Now when the several parts are 90 in the position as shown in Figs. 1 and 2, the needle valve I is held completely open, and when it is desired to close or partly close the needle valve I then the operator turns the handle N' in the direction of the arrow a' so that the arm O rides downward on the face cam N, whereby the threaded stem I' of the needle valve I is allowed to move downward by the action of the spring K pressing on the collar J to move the 95 needle valve I down toward the seat G. It will be seen that by the arrangement described the stem I' and the needle valve I are bodily moved in an axial direction on the operator turning the face cam N so that 100 screwing up of the needle valve stem is not required for adjusting the needle valve relative to its seat, as heretofore practised in

carbureters as now generally constructed. By adjusting the nut R on the collar Q the needle valve I may be set nearer to or farther from the valve seat G when assembling the several parts. The collar J is locked in place on the stem I' by a jam nut J', as indicated in Fig. 1. A spring S is coiled around the tube F and rests with its upper end on the under side of the cap plate F', while the lower end of the said spring S presses on top of the admission valve C so as to firmly hold the latter down on the top plate B of the casing A, to compensate for all wear between the conducting surfaces of the valve C and the top plate B. It will also be noticed that when the carbureter is in use, the suction action of the engine in drawing in the air causes the entering air to exert a pressure on the valve C to aid the spring S in holding the admission valve C in contact with the top plate B.

The bottom of the casing A is provided with an outlet T connected with the engine, and above the said outlet T and directly below the needle valve seat G is arranged a conical spreader U having a non-perforate point or apex U' and a perforate body portion U², so that the gasolene or other liquid flowing down the seat G drops onto the non-perforate apex U' to be spread by the same onto the perforate body portion U² to be taken up by the air entering the openings B', C² and passing through the perforate portion U² to the outlet T. The spreader U is supported by arms V from the bottom of the casing A so that the base of the spreader is a distance above the outlet T, as plainly indicated in Fig. 1.

From the foregoing it will be seen that by the arrangement described, the operator can properly control the admission of the air and that of the gasolene by operating the handles D and N' correspondingly.

Having thus described my invention, I claim as new and desire to secure by Letters Patent:—

1. A carbureter provided with a casing having an outlet in its bottom for the explosive mixture, and an air inlet opening in its top, an air admission valve mounted to turn on the casing, a valve seat in the said casing connected with a liquid fuel supply, a needle valve controlling the said valve seat, a tube on the casing and carrying the said valve seat at its lower end, a cap plate for the upper end of the tube, the stem of the needle valve passing through the said tube and cap plate, a member through which the needle valve stem passes and adapted when moved to move the needle valve, a guide connected with the air admission valve and with which said member has a sliding connection, a manually controlled means engaging said member for bodily moving the needle valve in the direc-

tion of its axis, and a spring surrounding the said tube and pressing on the air admission valve.

2. A carbureter provided with a casing having an outlet for the explosive mixture, 70 a valve seat in the said casing and connected with a gasolene supply pipe, a needle valve controlling the said valve seat, the said needle valve having a screw threaded stem, a collar screwed on the stem of the needle valve, a spring surrounding the stem of the needle valve and bearing on said collar to press the said needle valve in the direction of its seat, a face cam mounted to turn and under the control of the operator, the said needle valve stem passing through said face cam, an arm through which the needle valve stem passes, the said arm engaging said cam and adapted when moved to move the needle valve, an air admission valve, 85 and a guide rod having a sliding connection with the said arm.

3. A carbureter provided with a casing, a valve seat in the said casing and connected with a gasolene supply pipe, a needle valve controlling the said valve seat, a collar secured on the stem of the needle valve, a spring bearing on the said collar to press the said needle valve in the direction of its seat, a face cam mounted to turn and through which the stem of the needle valve extends, the said cam being under the control of the operator, an arm engaging the cam and adapted to be moved by the same, the needle valve stem passing through said arm, a member on the needle valve stem and engaged by said arm to move the needle valve, an air admission valve mounted to turn on the casing, a guide for said arm, and means for adjusting the tension of the said spring.

4. A carbureter provided with a casing, a valved air inlet in the casing, a valve seat connected with a gasolene supply, an outlet in the casing for the explosive mixture, a needle valve controlling the said valve seat and having a threaded stem, a tube on the said casing and carrying the said valve seat, the said needle valve stem passing through the tube, a collar fitting the said tube and secured on the said needle valve stem, a spring in the tube and pressing the said collar, a cap plate for the end of the tube, a face cam having a handle and mounted to turn on the said cap plate, an arm mounted on the said needle valve stem, a member adjustably mounted on the needle valve stem above the said arm and adapted to be engaged by the arm, the said arm riding on the said cam plate, and a vertical guide connected with the valve of said valved inlet and engaging an opening in one end of said arm, the said arm when the cam is turned in one direction, riding downward on the face cam under the action of said spring, to move the

needle valve toward its seat, the arm moving upward against the tension of said spring when the cam is turned in the opposite direction to move the needle valve from 5 the valve seat.

5. A carbureter provided with a casing having an air inlet, an air admission valve controlling said air inlet, a spring pressing on said air admission valve, a valve seat in 10 the said casing and connected with a liquid supply, a needle valve controlling the said valve seat and having a screw threaded stem, a spring pressing the needle valve in the direction of its seat, a collar screwing 15 on the upper part of the needle valve stem, an arm through which the said collar passes, a nut screwing on the said collar and resting on said arm, a guide with which said arm has a sliding connection, and a face cam 20 mounted to turn and through which said collar passes, the said cam actuating said arm to move the needle valve bodily from the valve seat.

6. In a carbureter a casing having an outlet for the explosive mixture, a top plate for said casing provided with an air inlet opening, an air admission valve mounted to turn on top of the said casing top plate, a valve seat connected with a liquid supply, a needle 25 valve controlling the said valve seat, a tube on the casing and carrying the said valve seat, the stem of the needle valve passing through the said tube, a cap plate for the upper end of the tube, a cam mounted to 30 turn on the cap plate, and a member mounted on the needle valve stem and riding on the said cam, a guide for said member, and a spring surrounding said tube and pressing 35 on the air admission valve.

40 7. A carbureter provided with a casing having an outlet in its bottom for the explosive mixture, a fixed top plate provided with an air inlet opening, an air admission valve mounted to turn on top of the said 45 casing top plate, a valve seat connected with

a liquid fuel supply, a needle valve controlling the said valve seat, a tube on the casing and carrying the said valve seat at its lower end, the stem of the needle valve passing through the said tube, a cap plate for the 50 upper end of the tube, a spreader below the valve seat and over the said outlet, a cam mounted to turn on the cap plate, an arm on the needle valve stem and riding on the cam, a vertical guide for said arm, and a 55 spring surrounding the said tube and engaging with its upper end the said cap plate, the lower end of said spring pressing on the said air admission valve.

8. A carbureter provided with a casing 60 having a fixed top plate provided with an air inlet opening and having a central upwardly extending flange, a tube screwing in the said flange and provided at its upper end with a cap plate and having a valve 65 seat at its lower end extending within the casing, the said valve seat being connected with a liquid fuel supply, a needle valve passing through the said tube and cap plate and controlling the said valve seat, an air 70 admission valve resting on top of the said top plate and having a hub mounted to turn on said flange, a spring coiled around the said tube and engaging with its upper end the under side of the cap plate, the lower 75 end of said spring pressing on the top of said air admission valve, a vertical rod held on said air admission valve, an arm adjustably connected with the needle valve stem and guided on said rod, and a manually 80 controlled cam mounted to turn on the cap plate and engaging the said arm.

In testimony whereof I have signed my name to this specification in the presence of two subscribing witnesses.
